UNITED STATES PATENT OFFICE.

TIMOTHY McGOLDRICK, OF LINCOLN, NEW HAMPSHIRE.

ARM-CUSHION FOR CRUTCHES AND FASTENINGS THEREFOR.

1,312,030.

Specification of Letters Patent.

Patented Aug. 5, 1919.

Application filed April 16, 1919. Serial No. 290,371.

To all whom it may concern:

Be it known that I, TIMOTHY McGOLDRICK, a citizen of the United States, residing at Lincoln, in the county of Grafton and State of New Hampshire, have invented 5 certain new and useful Improvements in Arm-Cushions for Crutches and Fastenings Therefor, of which the following is a specification, reference being had to the accompanying drawings.

This invention relates to an improved arm pit cushion for crutches, and one of the objects of the invention is to provide a cushion so constructed that it will readily fit the arm 15 pit of the crutch, whereby the user may be afforded comfort.

A further object of the invention is to provide an improved fastening for the opposite ends of the cushion, whereby the cushion 20 may be securely connected to the lateral extensions of the crutch. This fastening is of such a character that the cushion may be easily and quickly connected to or detached from the crutch.

25 A further object of the invention is to provide a fastening of this particular design, being constructed from sheet metal and in the form of a frame socket, which detachably receives the lateral extensions of the 30 crutch.

A further object of the invention is to so construct the fabric that forms the cushion, as to permit the cushion to set down in and conform to the arm pit of the crutch, thereby 35 by relieving the strain on the frame sockets or caps.

While the design and construction at present illustrated and set forth is deemed preferable, it is obvious that as a result of a reduction 40 of the invention to a more practical form for commercial purposes, the invention may be susceptible to changes, and the right to these changes is claimed, provided they are comprehended within the scope of what 45 is claimed.

The invention comprises further features and combination of parts, as will be hereinafter set forth, shown in the drawings and claimed.

50 In the drawings:

Figure 1 is a perspective view of the upper portion of a crutch showing the improved cushion and fastening means as applied thereto.

55 Fig. 2 is an enlarged detail view of the cushion detached.

Fig. 3 is a sectional view on line 3—3 of Fig. 1 that is through one of the frame sockets or caps.

Fig. 4 is an enlarged detail perspective 60 view of the other frame socket or cap, showing the parts thereof open.

Referring more especially to the drawings, 1 designates a cushion which is constructed to set down in and conform to the 65 arm pit of the crutch. This cushion may be constructed of any suitable fabric, such as velvet, plush, or the like, and comprises upper and lower pieces 2 and 3 which are stitched together as indicated at 4, so that 70 in between the upper and lower pieces suitable stuffing or padding 5 may be arranged, thereby providing a cushion. Attached to one end of the cushion in any suitable manner, for instance, by means of stitching, as 75 indicated at 6 is a frame socket 7. Stitching, which may be of heavy thread passes through the fabric of the cushion and through the apertures or openings of the parts of the frame socket, to securely connect the socket to the cushion. This frame socket consists of two metallic straps 8 and 9. The metallic strap 8 is formed into a ring shape and has its ends soldered as indicated at 10, thereby providing a band, to surround 80 one of the extensions 11 of the crutch. The metallic strap 9 is U-shaped and has its end portions soldered or otherwise connected, as indicated at 12 to diametrically opposite 85 portions of the band or ring. This metallic 90 U-shaped strap straddles the end of one of the lateral extensions 11 to limit the insertion of the lateral extension through the band or ring, as shown in the drawings.

The other frame socket or cap comprises 95 a metallic plate 13, which has apertures for the reception of stitchings or other fastening, as indicated at 14, whereby the plate may be securely connected to the opposite end of the cushion. An extension 15 projects from this plate and partially overlies the end of the other extension 11 of the crutch. A metallic strap 16 is hingedly connected to the extension strap 15 of said plate, as indicated at 17. This metallic strap 16 100 is provided with an elongated slot 18. The plate 13 has a lateral metallic extension strap 19 (which is somewhat pliable), and this extension strap 19 has a turn button 20 swivelly connected thereto in any suitable manner. The plate 13 is provided with a third extension strap 21, to which as at 22, a me- 105 110

metallic strap 23 is hingedly connected. This metallic strap 23 has a slot 24. It is to be noted that the extension 21 extends from the plate 13 at a point opposite the extension strap 19, and the extension 21 is at right angles to the extension 15. In connecting this latter frame socket to the other extension 11 of the crutch, the extension strap 19 is brought around in engagement with the extension 11, and then the turn button is disposed so as to enter the slot 24, thereby connecting the strap 23 to the extension strap 19. The turn button is then disposed, so as to enter the slot 18 of the strap 16, then the end head of the turn button is disposed with its center portion 25 in a position to prevent the disconnection of the strap 16. In order to detach this latter frame socket, the turn button may be manipulated, so that the metallic straps 16 and 23 may be disconnected from the turn button, and then subsequently opened, allowing the frame to be detached.

The invention having been set forth, what is claimed as new and useful is:

1. The combination with a crutch having an arm rest provided with lateral extensions, of a cushion engaging and conforming to said arm rest, a frame socket connected to one end of the cushion and receiving one of said extensions of the arm rest, a second frame socket connected to the other end of the cushion and having opening hinged parts adapted to receive the other extension of the arm rest, and means for detachably connecting the opening hinged parts.

2. The combination with a crutch having an arm rest provided with lateral extensions, of a cushion engaging and conform-

ing to the arm rest, a pair of frame sockets connected to the opposite ends of the cushion and receiving said extensions of the arm rest, one of said frame sockets comprising a metallic band encircling the extension that it receives, and a U-shaped metallic strap connected to the band and straddling the end of the extension received by the band, the other frame socket comprising a plate having oppositely arranged opening straps movable whereby they may encircle the other extension, said plate having another strap positioned on the plate at right angles to the opposite straps and being movable to engage the end of the other extension of the arm rest, and means for detachably connecting the ends of said straps.

3. The combination with a crutch having an arm rest provided with lateral extensions, of a cushion conforming to the arm rest, a pair of frame sockets connected to the opposite ends of the cushion and detachably receiving said extensions of the arm rest, one of said frame sockets comprising a body plate provided with opposite metallic straps, so movable as to permit them to encircle one of the extensions of the arm rest, said body plate having an additional metallic strap movable to engage the extremity of the extension received by the frame socket, and means for detachably connecting said straps.

In testimony whereof I hereunto affix my signature in the presence of two witnesses.

TIMOTHY McGOLDRICK.

Witnesses:

EDWARD S. NELSON,
E. W. CLEMENT.
